UNITED STATES PATENT OFFICE.

FREDERICK W. MOFFAT, OF WESTON, ONTARIO, CANADA.

DESIGN FOR A REFRACtORY FLOOR MEMBER FOR ELECTRIC FURNACES.

59,256.

Specification for Design.

Patented Oct. 4, 1921.

Application filed April 8, 1921. Serial No. 459,750. Term of patent 14 years.

To all whom it may concern:

Be it known that I, FREDERICK W. MOFFAT, a subject of the King of Great Britain, residing in the town of Weston, county of York, Province of Ontario, Canada, have invented a new, original, and ornamental Design for Refractory Floor Members for Electric Furnaces, of which the following is a specification, reference being had to the accompanying drawing, forming part thereof.

In the drawings:

Figure 1 is a side elevation; and
Fig. 2 an end view, showing my new design.

I claim:

The ornamental design for a refractory floor member for electric furnaces.

Signed at Toronto, Can., this 21st day of March, 1921.

FREDERICK W. MOFFAT.
